UNITED STATES PATENT OFFICE.

WALTER E. COFFIN, OF CLEVELAND, OHIO, ASSIGNOR TO THE NATIONAL
MALLEABLE CASTINGS COMPANY, OF CLEVELAND, OHIO, A CORPO-
RATION OF OHIO.

POCKET FOR COUPLINGS.

No. 835,726.

Specification of Letters Patent.

Patented Nov. 13, 1906.

Application filed June 12, 1906. Serial No. 321,382.

To all whom it may concern:

Be it known that I, WALTER E. COFFIN, of Cleveland, Cuyahoga county, Ohio, have invented a new and useful Pocket for Couplers, of which the following is a full, clear, and exact description, reference being had to the accompanying drawings, forming part of this specification, in which—

Figure 1 is a plan view of a coupler-pocket embodying my invention. Fig. 2 is a side elevation, partly in section; and Figs. 3 and 4 are detail views of the shims.

My invention is designed to overcome in a simple and practical manner the difficulty which has heretofore been experienced with the locomotive-couplers commonly employed, in the use of which as the tires and bearings of the engine wear and the springs become compressed the height of the coupler from the rail diminishes until finally it often happens that the coupler becomes too low to couple properly with the cars. This difficulty occurs even when the coupler is set originally at a greater height than would otherwise be proper. I have devised means by which this difficulty is entirely overcome in a simple and effective manner without providing special forms of multiple-part coupler-pockets and the like.

The invention consists in making the coupler-pocket with an integral pocket portion of greater height than the coupler-shank and providing adjusting devices, insertible and removable horizontally at the front of the pocket, by which as the wear above mentioned takes place the position of the shank in the pocket can be adjusted to compensate for such wear.

As shown in the drawings, I employ shims which are originally set on top of the shank between the shank and the top wall of the coupler-pocket, so as to fill the space therein and which for the purpose of adjustment can be removed horizontally through the flaring mouth of the pocket and replaced below the shank so as to elevate the shank above the bottom of the coupler-pocket. These shims are provided with holes through which the pivot-pin which connects the pocket to the coupler can pass. As an ex-

ample of the preferable dimensions of these parts I prefer to employ a coupler-pocket whose internal vertical height is about two inches greater than the vertical thickness of the coupler-shank and to place on top of the coupler-shank two shims each one inch in thickness. When the engine-body has settled one inch below its original height, one of the shims can be taken off the top and placed under the shank in the pocket, thus raising the height of the coupler one inch, and when further wear and settling to the extent of about one inch takes place the second shim can be transposed in like manner. In this way I can provide for the maximum wear to which the tires and other bearings of the locomotive are subjected before final repair or replacement is necessary. The passing of the pivot-pin through the shims is important, because after removing the pin the coupler and shims can be removed from the mouth of the coupler-pocket without dismantling the pocket, and when the pivot-pin is in place it holds the shims securely without need of other devices for that purpose.

In the drawings which show the preferable construction of my invention, 2 is the coupler-pocket having a flaring mouth, the internal cavity of the pocket being of greater height than the vertical thickness of the shank 3 of the coupler, and 4 5 are the shims which are placed between the top of the shank and the top wall of the pocket.

6 is the pin by which the coupler-shank is connected to the pocket and which, as above stated, passes through holes 7 in the shims.

I claim—

1. The combination of a coupler and coupler-pocket, the internal height of the coupler-pocket being greater than the vertical thickness of the coupler-shank, and a shim or shims removable horizontally from the front of the pocket for adjusting and holding the shank at variable positions vertically within the pocket, said shims having vertical passages 90 and a pin passing therethrough by which the coupler is connected to the pocket.

2. The combination of a coupler and flaring and integral coupler-pocket, the internal height of the coupler-pocket being greater 95 100

than the vertical thickness of the coupler-shank, and a shim or shims removable horizontally from the front of the pocket for adjusting and holding the shank at variable 5 positions vertically within the pocket and a pin passing through the shims and coupler-shank.

In testimony whereof I have hereunto set my hand.

WALTER E. COFFIN
